H. B. BÄTJER.

KNIFE SHARPENER.

APPLICATION FILED APR. 11, 1917.

1,275,833.

Patented Aug. 13, 1918.

UNITED STATES PATENT OFFICE.

HENRY BARTHOLD BÄTJER, OF NEW YORK, N. Y., ASSIGNOR TO H. MAIMIN CO., INC.,
A CORPORATION OF NEW YORK.

KNIFE-SHARPENER.

1,275,833.

Specification of Letters Patent. Patented Aug. 13, 1918.

Application filed April 11, 1917. Serial No. 161,196.

To all whom it may concern:

Be it known that I, HENRY BARTHOLD BÄTJER, a subject of Germany, residing at 28 Greenwich avenue, in the county of New York, State of New York, have invented certain new and useful Improvements in Knife-Sharpener; and I do hereby declare the following to be a full, clear, and exact description of the invention, such as will 10 enable others skilled in the art to which it appertains to make and use the same.

This invention relates to knife sharpeners and aims to provide means for sharpening a knife edge of the type in which the edge is not of great length but must be very keen when sharpened, such, for example, as the bottom chopping edge of a straight knife as used in cloth cutting machines.

The main object of the invention is to 20 provide an improved and simplified construction of the kind disclosed in the United States patent to Hyman Maimin, No. 1,186,488. The construction there shown comprises a pair of sharpening stones so 25 mounted that they may be caused to wipe alternately along the end surfaces of opposite sides of the knife at a proper angle to sharpen its edge.

The present invention involves the provision of improved supporting and actuating means for the stone carriers in which a plurality of frames or yokes, operatively connected to the carriers, are actuated by cam-means carried by an operating shaft 30 and adapted to impart to the frames and thus to the stone carriers, in an improved manner, the movements necessary to effect the sharpening of the knife edge. Preferably these frames or yokes are mounted 35 for sliding movements at right angles to each other, with one of the frames sliding on the other, whereby a single cam engaging both frames is effective to give to the stone-carriers the desired movement.

40 The invention will be understood more clearly from the following description when taken in connection with the accompanying drawing showing a preferred embodiment.

In this drawing Figure 1 shows the sharpener in side elevation, with a knife arranged in the field of operation of the grinder stones; Fig. 2 is an end elevation of the sharpener, looking toward the stones; Fig. 3 is a sectional view on line 3—3 of Fig. 2; 50 Figs. 4 and 5 are detail views showing re-

spectively the two frames or yokes actuated by the cam, Fig. 4 being partially broken away and partially in section.

As illustrated in the drawing, the knife sharpener is mounted on a suitable support 6; 60 a knife K being shown with its edge K arranged in position to be sharpened.

The construction of the sharpener is as follows: A guide block 7 is secured in place on support 6 by a pin or screw 8, and is provided with an extended hub 9 which passes through a recess in the lower end of the support. Journaled in this hub 9 is a crank shaft 10 carrying a crank 11 and a handle 12. Mounted for limited horizontal reciprocation on the guide-block 7 is a frame or yoke 13 having a tongue and groove connection with the guide-block. The yoke 13 has a guide-way 14 in which is mounted for limited vertical reciprocation a frame or yoke 15 held in place by a strap 16. On the end of shaft 10 is a cam 17 which rotates within the frames or yokes 13 and 15. The frame 15 has a depending arm 18 pivotally connected to a rocking bar 19 pivoted at 20 to 70 a central depending portion 21 of the horizontally reciprocating yoke 13. This rocking bar lies under arms 22 and 23 which act as carriers or supports for holders 24 and 25 within which are secured the stones 26 and 27. The arms 22 and 23 are carried by blocks 28 pivoted on pins 29 in depending ears of the frame 13. Coil springs 30 are preferably provided for the purpose of holding the arms 22 and 23 against the 80 engaging surfaces of the rocking-bar 19.

In operation, a rotation of the shaft 9 by means of the handle 12 will turn the cam 17. This will result in moving the sharpening stones 26 and 27 from side to side and 90 up and down. The cam is so shaped that the movement has the following sequence, beginning with the parts in the position shown in Fig. 2. In this position, the right hand stone is elevated, and the left hand stone 100 is depressed, and the sharpening attachment stands in an intermediate position of its sidewise movement, so that neither stone is in contact with the knife blade. A rotation of the cam in a counter-clockwise direction, as shown in Fig. 2, first moves the frame 13 to the right until the lowered stone 26 comes in contact with the edge of the knife and is pressed against it sufficiently to flex the edge somewhat and effect a good sharpening en- 110

gagement. Thereupon the sidewise movement of the frame 13 is discontinued and the further rotation of the cam lifts the frame 15 and causes an upward wiping movement of the stone 26 along the end surface of the knife at a fixed and proper sharpening angle thereto. While this sharpening movement of the stone is in progress, the frame 13 stands still, and after the stone 10 26 is entirely lifted and the other stone is entirely depressed, further rotation of the cam moves the frame 13 to the left, bringing the now lowered stone 27 into like sharpening contact with the other side of the knife 15 edge, whereupon the sidewise movement is stopped and the second stone is wiped along the surface of the knife, likewise at a proper sharpening angle thereto, while the other stone out of contact with the knife edge is 20 depressed. At the end of this movement the cam comes back to the position shown in Fig. 2.

It will be observed that in the construction above described, the stones are singly 25 and alternately wiped along the opposite sides of the knife, at a fixed and predetermined sharpening angle thereto, by means of an operating mechanism comprising a cam and yoke structure in which a plurality 30 of reciprocating yokes or frames are actuated by a single cam mounted on a cam shaft the axis of rotation of which is fixed relative to the field of operation of the sharpening stones.

35 I claim:

1. A knife sharpener comprising a support, a frame reciprocable on the support, a second frame reciprocable on the first frame, stone supports pivotally mounted on one 40 frame, means for rocking the stone supports on their pivots actuated by the other frame, and means for reciprocating both frames to apply the stones alternately to opposite sides of the knife for sharpening; substantially as 45 described.

2. A sharpener comprising a fixed support, a shaft journaled in the support, cam-means on the shaft, a pair of stones, and means for supporting the stones actuated by 50 the cam-means to apply the stones alternately to the opposite sides of the knife to sharpen the same; substantially as described.

3. A sharpener comprising a support, a cam pivoted on the support, a plurality of 55 yokes movable on the support and adapted to be actuated by the cam, a pair of stones, and a pair of stone supports therefor movably mounted on one of the yokes and operatively connected to the other yoke, whereby 60 rotation of the cam moves the yokes to apply the stones alternately to opposite sides of the knife to be sharpened; substantially as described.

4. A sharpener comprising a support,

frames on the support arranged for reciprocation in different directions, stone carriers and stones thereon adapted to be arranged on opposite sides of the knife, operative connections between the frames and the stone carriers whereby the stones are applied alternately to the opposite sides of the knife when the frames are reciprocated, and means for reciprocating the frames; substantially as described. 65

5. A knife sharpener comprising a support, a frame horizontally reciprocable on the support, stone carriers pivoted on the frame, stones on the carriers adapted to be arranged on opposite sides of the knife, a frame vertically reciprocable on the support 70 operatively connected to the stone carriers, and rotary means for reciprocating the frames in timed relation to apply the stones alternately to opposite sides of the knife for sharpening; substantially as described. 75

6. A sharpener comprising a support, a slide carried by the support, a second slide carried by the support for movement at right angles to the first slide, stone supports pivoted on one of the slides, stones on the 80 supports, a member pivoted on one of the slides and engaging the stone supports, an operative connection between said pivoted member and the slide other than the slide on which said member is pivoted, and means 85 for moving the slides, whereby the stones are alternately applied to opposite sides of the knife to sharpen the same; substantially as described. 90

7. A sharpener comprising a support, a cam pivoted thereon having a single continuous periphery, a plurality of stones, and operative connections between the stones and the cam including a member on the support moved by the cam and stone carriers movable on said member when the member is moved on the support by the cam whereby upon rotation of the cam the stones are applied alternately to opposite sides of the knife; substantially as described. 100

8. A sharpener comprising a pair of stone supports, stones on the supports adapted to be arranged on opposite sides of the knife, and means for actuating the stone supports to apply the stones alternately to opposite 105 sides of the knife for sharpening, such means comprising a plurality of movable yokes operatively connected to the stone supports and rotary means for moving the yokes in timed relation; substantially as described. 110

9. A sharpener comprising a support, a cam pivoted on the support, means for rotating the cam, a horizontal frame moved from side to side by the cam, a pair of stone supports pivoted to the frame, stones on the 115 supports, a lever pivoted to the frame and engaging both supports, and a vertical frame moved up and down by said 120

cam to rock the lever to cause the stones to have movements toward and away from the knife; substantially as described.

10. A sharpener comprising a support, 5 cam-means pivoted on the support, horizontally and vertically reciprocating frames on the support adapted to be actuated by the cam means, a pair of arms pivoted on one of the frames for rotation about converging

axes, operative connections between the two 10 frames and said arms, and stones on the swinging ends of said arms, whereby actuation of the cam-means causes the stones to be applied alternately to opposite sides of the knife; substantially as described. 15

In testimony whereof I affix my signature.

HENRY BARTHOLD BÄTJER.
